CLAIM

The ornamental design for a remote keypad dialer, as shown and described.

DESCRIPTION

FIG. 1 is a top, right, front, perspective view of a remote keypad dialer;

FIG. 2 is a left elevation view thereof;

FIG. 3 is a rear elevation view thereof;

FIG. 4 is a top plan view thereof; and,

FIG. 5 is a bottom plan view.

The broken lines shown throughout the views are for illustrative purpose only and form not part of the claimed design.

*FIG. 1**FIG. 2**FIG. 3**FIG. 4**FIG. 5*
